(57) **CLAIM**

The ornamental design for a FAUX BUTTON as shown and described.

DESCRIPTION

FIG. 1 is a perspective view of a faux button showing my new design;

FIG. 2 is a top view thereof;

FIG. 3 is a bottom view thereof;

FIG. 4 is a right side view thereof, the left side view being a mirror image thereof;

FIG. 5 is a right side cross-sectional view thereof, the cross-section being taken along line 5 shown in FIG. 4;

FIG. 6 is a left side cross-sectional view thereof, the cross-section being taken along line 6 shown in FIG. 4;

FIG. 7 is a perspective view of a faux button showing my new design shown in a state of use;

FIG. 8 is a top view thereof;

FIG. 9 is a bottom view thereof;

FIG. 10 is a right side view thereof, the left side view being a mirror image thereof;

FIG. 11 is a right side cross-sectional view thereof, the cross-section being taken along line 11 shown in FIG. 10;

FIG. 12 is a left side cross-sectional view thereof, the cross-section being taken along line 12 shown in FIG. 10;

The features shown in or surrounded by broken lines in the various Figures are for illustrating environmental structure and form no part of the claimed design.
